UNITED STATES PATENT OFFICE.

JAMES B. HANLEY, OF PHILADELPHIA, PENNSYLVANIA.

SHOE HEEL.

Application filed May 2, 1921. Serial No. 466,158.

To all whom it may concern:

Be it known that I, JAMES B. HANLEY, a citizen of the United States, residing at Philadelphia, in the county of Philadelphia and State of Pennsylvania, have invented 5 certain new and useful Improvements in Shoe Heels, of which the following is a specification.

One object of my invention is to make a 10 resilient heel structure for shoes which will be an improvement over various known forms of rubber heels; the construction of my improved heel being such that it will absorb shocks and at the same time will be 15 extremely durable and when worn upon a shoe will enable a person to walk more easily and comfortably.

Another object is to so construct my improved heel that it can be easily manufactured and attached to or detached from a 20 shoe.

These objects, and other advantageous ends which will be described hereinafter, I attain in the following manner, reference 25 being had to the accompanying drawings in which—

Figure 1 is a side elevation showing my improved heel attached to a shoe,

Figure 2 is a section taken on the line 30 2—2 of Figure 1,

Figure 3 is a sectional plan view taken on the line 3—3 of Figure 1 and drawn on a slightly enlarged scale,

Figure 4 is a section taken on the line 4—4 35 of Figure 3,

Figure 5 is a section taken on the line 5—5 of Figure 3,

Figure 6 is an inverted plan view of the 40 attachment plate with the plungers mov- ably secured thereto,

Figure 7 is a detached top plan view of the lift-retaining band,

Figure 8 is a fragmentary perspective 45 view of a portion of said lift-retaining band, and

Figure 9 is an elevation of one of said plungers and its retaining ring detached; the bottom of the plunger being shown in section.

Referring to the drawings, 10 represents 50 an attachment plate which is preferably made of light weight metal and has a peripheral flange 11 which projects above the top surface 12 and below the bottom surface

13. This plate at one end has a recess 14 55 as shown in Figures 3 and 6 and the outer surface of the flange 11 is concaved in vertical cross section as shown at 15 in Figures 4 and 5. The provision of the flange 11 produces a space 16 above the surface 12 60 and another space 17 below the surface 12; both of said spaces being bounded by the flange 11. The plate 10 has holes 18 through which slide the stems 19 of plungers 20. The lower end 21 of the plungers, which 65 are of greater diameter than the stems 19, have flanges 22 and cavities 23 in their bottom surfaces so as to form inverted cups as shown in Figure 9. The upper ends of the stems 19 have annular 70 grooves 24 into which are adapted to be sprung split resilient rings 25 by forcing said rings over the upper tapered ends 26 of the stems 19.

Coiled springs 27 surround the stems 19 75 and parts 21 of the plungers 20 and have their opposite ends in respective engagement with the surface 13 of the plate 10 and the upper surface of the flanges 22 so as to move the plungers downwardly. The upper part of the plate 10 has depressions 28 80 into which the rings 25 move due to the action of the springs 27; said rings abutting the inner parts of the depressions 28 and thereby limiting the downward movement 85 of the plungers. The springs 27 are preferably made by coiling lengths of wire which are thinner at their ends than at parts between the ends so that the end portions of the springs can more easily flex than the intermediate portion thereof.

A lift 29, which is preferably made of rubber, has a continuous flange 30 which projects upwardly from the bottom portion 31. This flange 30 of the lift is adapted to engage the concave surface of the flange 11 of the attachment plate and a clamping band 32 surrounds the outer surface of the lift flange 30 and is adapted to compress 95 said flange 30 and hold it within the concavity of the flange 11 of the attachment plate. The clamping band 32 may be made of a strip of resilient metal having its end portions 33 adapted to be positioned within the recess 14 and a clamping member 34 is 100 adapted to engage the end portions 33 of the clamping band and to move them toward each other while within the recess 14 so as 105

to draw the clamping band into tight fitting engagement with the outer surface of the lift flange 30. This clamping member 34 is illustrated in the form of a block which is secured to the attachment plate by a screw 35; said screw entering a tapped hole in the attachment plate and passing between the end portions 33. The outer surface of the end portions 33 are preferably slightly indented as shown at 36 and the clamping member has a portion 37 as shown in Figure 4 which enters the indentation 36 and when the clamping member 34 is screwed inwardly the end portions 33 will be moved toward each other to form the clamping action of the band 32 so as to compress the lift flange 30 and thereby secure the lift to the attachment plate 10.

The lower ends of the plungers 20 are adapted to engage the upper surface 38 of the portion 31 of the lift so as to normally hold the portion 31 of the lift under a slight tension; a portion of the rubber plungers 20 so as to prevent the lower ends of the plungers from shifting laterally from their predetermined normal positions.

The heel can be attached to the body portion 39 of the shoe by means of screws 40 before the lift and clamping band are placed in position; said screws extending through the attachment plate and into the bottom of the body portion 39 of the shoe.

The outer surface of the portion 31 of the lift is preferably made slightly convex without any sharp edges so as to conform to the shape of the bottom of the human heel.

and during walking action the shocks will be taken up jointly by the spring-pressed plungers and also by the resilient character of the lift; the plungers by being arranged as clearly shown in Figure 6 are so disposed that they will resist shocks imparted at practically every portion of the heel and due to this disposition of the plungers and the yielding action of the lift both due to its own resiliency and to the resiliency pro-

vided by the springs, the bottom portion 31 will not readily wear out to destroy the shape of the heel as do the solid rubber heels made prior to my invention.

The clamping band 32 can be made of a width substantially similar to the width of the flange 11 of the attachment plate and this band on its outer surface can be colored to correspond with the color of the body portion of the shoe and if desired the lift can be made of a corresponding color so as to present a neat appearance.

While I have described my invention as taking a particular form, it will be understood that the various parts of my invention may be changed without departing from the spirit thereof, and hence I do not limit myself to the precise construction set

forth, but consider that I am at liberty to make such changes and alterations as fairly come within the scope of the appended claims.

Having thus described my invention, what I claim as new and desire to secure by Letters Patent is:—

1. A heel including an attachment plate having a peripheral portion provided with an outer concaved surface; a lift having a flange extending upwardly along said surface; a band surrounding said flange; and means for forcing said band into said flange and thereby compressing said flange into said concaved surface of the peripheral portion.

2. A heel including an attachment plate having a peripheral portion provided with an outer concaved surface and a recess; a lift having a flange extending upwardly along said surface; a band surrounding said flange and having enlarged ends; a clamping member and means for forcing the ends of said band into said flange in said recess and thereby compressing the flange in said concaved surface of the peripheral portion.

3. A heel including a tread portion having an enlarged upwardly extending flange before the lift and clamping band are adapted to flex; an attaching plate having a concaved portion receiving said flange; securing means including a band and means for forcing it into said flange for anchoring the flange in said concaved portion of the attaching plate; and cushioning springs with guide means between the plate and the tread portion.

4. A heel including an attachment plate having a flange providing an upwardly extending portion, said plate having holes within the confines of said portion; a lift secured to said plate and having a bottom spaced below the plate; plungers slidably mounted in said holes; and springs for holding said plungers against said bottom portion of the lift; substantially as described.

5. A heel including an attachment plate; a rubber lift secured to said plate and having a bottom portion spaced below said plate; and spring-pressed plungers in said space, said plungers having cupped ends in engagement with said bottom portion of the lift; substantially as described.

6. A heel having an attachment plate with holes therein; a lift having its bottom spaced below said plate; spring-pressed plungers for engagement with said bottom lift and having stems slidable within said holes, said stems having grooves; and split spring

posed between said plate and the bottom of the lift and serving to resiliently resist relative movement of the plate and lift bottom toward each other, said springs being more easily flexible adjacent their ends than at intermediate parts; substantially as described.

In testimony whereof I have signed my name to this specification in the presence of two subscribing witnesses.

JAMES B. HANLEY.
